UNITED STATES PATENT OFFICE.

LOUIS M. BROWN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

INSOLE-MARKING MACHINE.

1,273,452.

Specification of Letters Patent.

Patented July 23, 1918.

Application filed November 19, 1913. Serial No. 801,807.

To all whom it may concern:

Be it known that I, LOUIS M. BROWN, a citizen of the United States, residing at Beverly, in the county of Essex and State of Massachusetts, have invented certain new and useful Improvements in Insole-Marking Machines; and I do hereby declare the following to be a full, clear, and exact description of the invention, such as will 10 enable others skilled in the art to which it appertains to make and use the same.

The present invention relates to marking machines and more particularly to machines for applying markers to soles or 15 insoles to serve as guides for the operator in performing some subsequent operation upon the shoe.

The object of the invention is to provide a novel and improved construction by 20 which a plurality of guiding or locating lines may be accurately and conveniently impressed upon soles either before or after they have been attached to the last.

To this end one feature of the invention 25 contemplates the provision of mechanism whereby an insole may be marked after it has been secured to the last, the position of the mark or marks being preferably determined from the last, thus avoiding in- 30 accuracies due to distortion of the sole either during the channeling or after chan- neling and prior to the assembling of the parts upon the last.

In accordance with a further feature of 35 the invention the sole is positioned length- wise by a fixed toe gage, with reference to which the marking devices for applying the several marks to the insole are adjusted. This insures an accurate positioning of the 40 marks even when the soles are marked before being attached to the last, since variations in the length of the soles caused by the channeling are commonly rectified by trimming the heel end of the sole after it 45 is attached to the last.

These features as well as the further features hereinafter described and set forth in the claims will be readily understood from an inspection of the accompanying draw- 50 ings and the following detailed description of the mechanism illustrated therein.

In the drawings:

Figure 1 is a front elevation of the machine embodying the invention in its pre-

furred form; Fig. 2 is a plan view of the 55 machine; Fig. 3 is a transverse sectional view; Fig. 4 is a detail plan view showing the marker carrying blocks, the markers being removed; Fig. 5 is a detail vertical sectional view through the toe positioning de- 60 vices; Fig. 6 is a detail elevation showing the rear side of one of the marker carrying blocks; Fig. 7 is a front elevation of the sole supporting and positioning devices adapted to support and position a sole prior 65 to its attachment to the last; and Fig. 8 is an end elevation of the devices shown in Fig. 7.

The machine illustrated comprises de- 70 vices for positioning the sole and for mark- ing thereon the tip line, the ball line and heel breast line so that the operator may be guided and assisted in assembling the parts, in lasting the shoe, in sewing the inseam, in butting the welt, and in performing other 75 operations on the shoe.

In the construction shown, the marking and sole positioning devices are mounted and guided upon a base plate 2 which may be supported in a horizontal or inclined 80 position by any suitable standard (not shown).

Each marking device comprises a series of marking blocks 4 mounted in a carrier 6 and supported upon springs 8 so that they 85 may yield independently to conform to the curvature of the sole being operated upon. Each marker is pivotally supported to swing about a vertical axis in a bearing formed in block 10 at the end of the arm 90 22 which is attached to the block. The block 10 with a marker pivoted therein is mounted to slide in a guideway formed in the base plate. The angular position of each marker transversely of the guideway 95 and of the sole is determined by spring pressed stop pins 12 arranged to engage recesses in the under side of the carrier 6.

In order that the angular adjustment of a marker may be readily and accurately re- 100 versed for right and left shoes two pins are provided for each marker, and means is also provided for adjusting the pins equal distances in opposite directions in varying the angular adjustment of the marker. As 105 shown, the pins 12 are carried in blocks 14 guided in a bracket 16 secured to the bearing block 10. The blocks 14 are engaged by

right and left hand screw threads formed on an adjusting shaft 18 mounted in the bracket and held from longitudinal movement by a plate 20 secured to the bracket 5 and having a slotted end which engages a groove formed in the middle of the shaft. When the pins are in neutral position, or in position to engage both recesses in the carrier 6, as shown in Fig. 6, they hold the 10 marker at right angles to the guideway in the base plate. The marker is thus positioned when its angular position remains the same for both right and left shoes. When the shaft is turned to separate the 15 pins 12, they will be moved equally from their neutral position and if one pin is positioned to hold the marker in proper angular relation for a right shoe the other will be in position to hold the marker in 20 the reverse angular relation or in correct position for a left shoe. The change for rights or lefts can, therefore, be quickly made by swinging the marker to bring the proper recess in its carrier into engagement 25 with the corresponding stop pin.

The marker carrying blocks 10 are adjusted in the guideway to bring the markers into proper relation to each other and to the sole positioning devices for soles of different 30 sizes by differential adjusting mechanism which simultaneously adjusts the markers, and this mechanism is so constructed that the markers may be independently adjusted to bring them into proper relation for different styles of soles. As shown, the blocks 35 10 are provided with laterally projecting arms 22 which are provided at their outer ends with screw threaded bosses 23 engaging screw threads of different pitch formed on 40 the shafts 24 and 26 which extend longitudinally of the base plate. The adjusting screw 28 for the breast line marker is formed on the shaft 24, while the adjusting screws 30 and 32 for the tip line marker and ball line 45 marker are formed on two sections of the shaft 26 which is in the form of a sleeve surrounding the shaft 24. The section on which the screw 32 is formed is secured to the other section of the shaft 26 by a set 50 screw 34 which may be loosened to enable the screw 32 to be independently turned to adjust the ball line marker independently of the other markers. The shafts carrying the 55 adjusting screws are turned in unison to effect the differential adjustment of the markers for different sizes by a common actuator connected with the shafts through proper gearing. As shown, the actuator consists of a shaft 36 carrying a knurled 60 operating head 38 and a gear 40 which meshes with a pinion 42 secured to the upper end of a shaft 44, the lower end of which carries two beveled gears 46 and 48 meshing with similar gears 50 and 52 secured to the 65 shafts 26 and 24, respectively. The gear 40

is provided with graduations which coöperate with a stationary pointer 54 in indicating the adjustment for different sizes. The shaft 26 is free to slide in its bearings and is held in position with the gear 50 in engagement with the gear 46 by a pivoted latch 56. This latch may be thrown up so that the shaft 26 may be moved on the shaft 24 to disengage the gears 50 and 46, thus enabling the shafts 24 and 26 to be turned 75 independently to effect independent adjustment of the markers.

The devices for supporting and positioning the sole are carried upon a vertically movable frame comprising the cross bar 58 and the two guide rods 60 and 62 which are mounted to slide in bearings 61 at the ends of the base plate. The rod 62 is provided at its upper end with a head 64 which is grooved to receive a sole supporting block 66. The sole supporting block is provided with a horizontally projecting toe support 68 and with a vertical face 70 forming a fixed toe gage against which the end of the toe is positioned. The toe of the sole is positioned laterally by a V-shaped toe gage 72 arranged to engage the toe of the last and mounted to slide on the block 66. The toe gage is held on the block by a pin 74 passing through a slot 75 in the block 66 and the gage is forced forward by a spring 76. The guide rod 60 is provided at its upper end with a support 78 grooved to receive the base of a bracket 80 which is secured in the support by a clamping screw 82. The bracket 80 carries a heel support 84 which is pivoted on the bracket and may be adjusted vertically by the adjusting screw 86. The heel of the sole is positioned laterally by a V-shaped heel gage 88 arranged to engage the heel of the last and provided with a shank 90 mounted to slide in the bracket 80. The heel gage is held in the bracket by a pin 92 lying in a slot in the upper end of the bracket and is forced forward by a spring 94. The spring 94 which forces the heel gage forward is stronger than the spring 76 which acts upon the toe gage so that the toe of the sole or last is forced against the fixed toe gage 70 when the last and attached sole are placed in position upon the supports.

The V-shaped gages 72 and 88 center, or laterally and angularly adjust the insole with respect to the longitudinal axis of the machine in order to set the insole in the proper position so that the transverse marks to be placed thereon will be located in the correct angular relation to the insole axes.

The sole supporting frame is held in raised position by springs 95 and is moved downward to press the surface of the sole against the markers by pressure applied to the last after it has been positioned upon the heel and toe supports.

The markers are inked by an inking roll 96 mounted in a yoke 98 which is secured to the end of a slide rod 100. The rod 100 is mounted to slide in a bearing 102 formed at 5 the end of an arm 104 which projects from the base plate. The inking roll is reciprocated by a lever 106 pivoted to the arm 104 and connected at its upper end to the yoke 98 by a link 108. The lower end of the lever 10 106 carries a roller 110 which engages a cam groove 112 formed in an arm 114 projecting from the cross bar 58 of the sole supporting carriage. As the sole supporting carriage is moved up and down the cam groove 112 acts 15 to move the inking roll back and forth across the marker, the roll being drawn back out of the path of the sole as the sole is moved down into engagement with the markers.

The sole supporting devices above described are adapted to support and position a sole after it has been attached to the last. In Figs. 7 and 8 a sole supporting device is shown which may be used in the machine to mark soles before they have been attached to 20 the last. As shown in these views, the sole supporting and positioning devices comprise a plate 116 which is supported upon arms 118 journaled upon a supporting rod 120. The rod is supported in brackets 122 and 124 25 which are adapted to be secured to the support 78 and head 64, respectively, of the sole supporting carriage. The sole carrying plate 116 is provided with a fixed toe gage 126 against which the end of the insole rests 30 and with a V-shaped toe centering gage 128 which is mounted to slide upon the plate and is pressed forward by a spring 130 in order to provide for different style insoles. Thus an insole with a wide toe will press the V- 35 gage back farther than an insole with a narrow toe, and this adjustment allows the end of the insole to be fixed against the gage 126, while the V-gage centers the toe regardless of the style of the insole. The plate 116 is 40 also provided with a V-shaped heel centering gage 132 carried by a slide 134 mounted in a guideway formed in the plate. The heel gage may be moved toward and from the toe gage by a handle 136 and it is held friction- 45 ally in position by a spring pressed pin 138 which engages the bottom of the guideway in which the slide 134 is mounted. The plate 116 is held normally in the position indicated in dotted lines at the right of Fig. 8 50 by springs 140 connected with the rod 120 and engaging two of the arms 118. The center arm 118 is provided with a handle 142 by which the plate may be swung into the dotted line position indicated at the left in 55 Fig. 8 after the sole has been positioned on the plate. The sole is held on the plate by a leaf spring 144. When the plate is swung down into the position indicated in dotted lines at the left in Fig. 8, a stop 146 on one 60 of the arms 118 engages a stop 148 on the

bracket 122 and thereafter the sole may be moved down into engagement with the markers by pressure upon the handle 142.

While it is preferred to employ the specific construction and arrangement of parts 70 shown and described it will be understood that this construction is not essential to the broader features of the invention and may be varied or modified without departing therefrom.

Having explained the nature and object of the invention and specifically described one form of apparatus in which it may be embodied, what I claim is:—

1. A machine for marking insoles, having 80 in combination, means for supporting and positioning the insole, a tip line marker, a ball-line marker, and a breast-line marker, all adjustable relatively to one another for operating on soles of different size, and 85 mechanism for relatively actuating the markers and the insole supporting means to mark the insole.

2. A machine for marking insoles, having 90 in combination, a fixed toe gage for positioning the insole longitudinally, means for positioning the insole laterally, a plurality of marking devices adjustable relatively to one another and to the toe gage to correspondingly mark the insole transversely at 95 different points along its length for the different sizes of shoes.

3. A machine for marking insoles, having 100 in combination, a fixed toe gage for positioning the insole longitudinally, a plurality 100 of markers relatively adjustable to one another and to the toe gage to correspondingly mark the insoles for the different sizes of shoes, and a common actuator for simultaneously adjusting the markers varying 105 amounts with relation to the toe gage.

4. A machine for marking insoles, having 110 in combination, means for supporting and positioning an insole, a tip line marker, a ball-line marker, a breast-line marker, all angularly adjustable with relation to one another and mechanism for relatively actuating the markers and insole supporting means to mark the insole.

5. A machine for marking insoles, having 115 in combination, means for supporting and positioning an insole, a tip line marker, a ball-line marker, a breast-line marker, means to adjust said markers bodily and angularly to mark the insole at different distances and 120 at different angles, and mechanism for relatively actuating the markers and insole supporting means to mark the insole.

6. A machine for marking insoles, having 125 in combination, insole positioning means including a fixed toe gage for positioning the insole longitudinally, and V-gages for centering the toe and heel of the insole, and a marking device for marking the insole.

7. A machine for marking insoles, having 130

in combination, a fixed end gage for positioning the insole longitudinally, a yielding centering device supported on the end gage and arranged to yield longitudinally for centering the end of the insole, and a marking device for marking the insole.

8. A machine for marking insoles, having in combination, means for supporting and positioning the insole, a plurality of marking devices adjustable relatively to one another and to the insole positioning means, a common actuator for simultaneously adjusting the marking devices different amounts, and connections between said actuator and said marking devices having provision for the independent adjustment of each of said marking devices.

9. A machine for marking insoles, having in combination, means for supporting and positioning an insole, a plurality of marking devices, a shaft for adjusting one of said marking devices, a sleeve rotatably mounted upon said shaft for adjusting another of said marking devices, a common actuating shaft for said first mentioned shaft and sleeve, and gearing interposed between the actuating shaft and said first mentioned shaft and sleeve to simultaneously adjust the marking devices different amounts.

10. A machine for marking insoles, having in combination, means for supporting and positioning the insole, a plurality of marking devices relatively adjustable with respect to one another and to the positioning means, and mechanism for adjusting said devices comprising a hollow shaft, a second shaft rotatably mounted within said hollow shaft, one of said shafts comprising two portions rotatably adjustable with relation to each other, and each provided with screw threads differing in pitch from the other, a common actuator for said shafts, and connections between said actuator and shafts having provision for the actuation of one shaft independently of the other.

11. A machine for marking insoles, having in combination, means for supporting and positioning an insole, a marking device located below the insole supporting means, and mechanism for relatively actuating the marking device and the insole supporting means to mark the lower face of the insole.

12. A machine for marking insoles, having in combination, a frame, a marking device supported therein, insole supporting means located above the marking device and vertically movable with respect to said marking device, and means for guiding the supporting means in their vertical movements.

13. A machine for marking insoles, having in combination, means for supporting

and positioning the insole, an angularly adjustable marking device, and mechanism for securing said marking device in the same angular adjustment in opposite directions for right and left insoles, said means comprising spring-pressed stop pins, carriers for the same, and a right and left hand threaded shaft for adjusting said pins equal distances in opposite directions.

14. A machine for marking insoles having, in combination, a plurality of marking devices for marking the insole, means for relatively, longitudinally and angularly adjusting the markers to position them for placing marks in predetermined positions on a determined type of sole, and means for supporting and positioning longitudinally and centering a last having an insole attached thereto with respect to the longitudinal and angular position of the markers.

15. A machine for marking insoles on the last having, in combination, a marking device for marking the insole, means for relatively, longitudinally and angularly adjusting the marking device for placing a mark in a predetermined position on a determined type of sole, and a last positioning means including a fixed toe gage for positioning the insole longitudinally, and means for centering the last with respect to the longitudinal and angular position of the marking device.

16. A machine for marking insoles having, in combination, a marking device for marking the insole, means for relatively, longitudinally and angularly adjusting the marker for placing a mark in a predetermined position on a determined type of sole, an adjustable heel gage, and a toe gage cooperating with the heel gage for positioning longitudinally a last having an insole attached thereto and for centering said last with respect to the longitudinal and angular position of the marking device.

17. A machine for marking insoles, having, in combination, a fixed toe gage for positioning a last having an insole attached thereto longitudinally, means for positioning the last laterally, a plurality of marking devices adjustable relative to one another, and means for relatively actuating the marking devices and positioning means to mark the insole.

18. A machine for marking insoles, having, in combination, means for positioning and supporting a last having an insole attached thereto, a plurality of marking devices relatively adjustable to one another and located below the insole, means for adjusting the markers and mechanism for relatively actuating the markers and the supporting means to mark the insole.

19. A machine for marking insoles having, in combination, a fixed toe gage for positioning the insole longitudinally, means for positioning the insole laterally, a tip line

marker, a ball line marker and a breast line marker, means for adjusting said markers relatively to one another and to the toe gage to correspondingly mark insoles for different sizes of shoes, and mechanism to relatively actuate the markers and the insole supporting means to mark the insole.

20. A machine for marking insoles having, in combination, an end gage for positioning the insole longitudinally, a ball line marker, a breast line marker and a tip line marker, said markers being relatively adjustable to the end gage to correspondingly mark insoles for different sizes of shoes, and 10 a common actuator for simultaneously adjusting the markers varying amounts with relation to the end gage.

21. An insole fitting machine having, in combination, a fixed end gage for positioning the insole longitudinally, a longitudinally yieldable fork coöperating with the said gage for centering the end of the insole, means for holding the insole against said gage, and devices for operating on the insole.

22. An insole fitting machine having, in combination, a fixed toe gage, a spring, a toe centering fork coöperating with said gage mounted to move longitudinally against 30 said spring, a heel centering fork mounted to move longitudinally, a spring of greater strength than the spring operating on the toe fork arranged to move the heel fork toward the toe fork to press the insole against 35 the gage, and means for operating upon the insole.

23. A machine for marking an insole attached to a last, having, in combination, means for supporting the last, means for

longitudinally positioning and centering the 40 last and insole, a marking device for placing a line on the insole comprising a plurality of independently yielding sections, mechanism for intermittently inking the marker, and means to relatively move the marker 45 and last and insole to bring the insole into contact with the marker whereby the marker will conform with its marking edge to the sole contour to make a continuous line.

24. The combination with means for operating on a sole, of a gage to engage one end of a sole and position the sole longitudinally with relation to said operating means, and a longitudinally yielding centering fork to engage the same end of the sole. 50 55

25. A machine for marking insoles, having, in combination, means for supporting and positioning a last having an insole attached thereto, a plurality of marking devices to mark the insole at different points 60 in its length, means for relatively adjusting the marking devices for shoes of different sizes, and means for relatively actuating the marking devices and last supporting means to mark the insole. 65

26. A machine for marking insoles, having, in combination, means for supporting and positioning a last having an insole attached thereto, a plurality of independently yielding marking devices to mark the sole 70 at different points in its length, and means for relatively actuating the marking devices and last supporting means to mark the insole.
